HYDRAULIC COMPRESSOR

Serge Raymond Seillière, Paris, France

Application December 24, 1931, Serial No. 583,042.
Renewed October 12, 1934. In France December 27, 1930

9 Claims. (Cl. 230—85)

The present invention relates to hydraulic gas compressors. In these devices as hitherto employed a liquid is driven by the aid of a piston into a chamber which contains the gas to be compressed. When the piston moves in one direction it compresses the gas which is expelled from the chamber through a check valve. On the return movement of the piston the liquid is drawn out thereby causing a reduction of pressure in the chamber and consequently an inflow of a new gaseous mass through the suction valve.

The valves of a compressor can only operate satisfactorily if the frequency of their movement is low; hence the necessity to employ pistons with large dimensions which are moved slowly. For this reason it is not possible to operate these pistons directly by means of a high speed motor and the complete installation is thus rendered cumbersome and expensive.

The object of the present invention is to overcome the above disadvantages and to provide an hydraulic compressor in which the frequency of the movements of the compressor valves is independent of the speed of rotation of the pump. This permits the construction of high speed compressors the movements of each valve of which may be as slow as desired and moreover, which permits the use of hydraulic pumps, such as centrifugal pumps, which are simpler and lighter than piston pumps.

The compressor forming the object of the present invention comprises essentially two identical chambers which are filled with the same predetermined quantity of liquid which circulates from one chamber to the other under the action of one or more pumps. These pumps are preferably of the centrifugal type or, at least exhibit the same hydraulic characteristics as centrifugal pumps.

When the pressure diminishes in one chamber the liquid therein will flow out and pass into the second chamber where it compresses a new supply of gas. By employing a suitable valve the compressed gas may be collected in a reservoir.

If it is assumed, for instance, that the quantity of the displaceable liquid is sufficient to occupy $\frac{1}{2}$ of the capacity of one of the chambers and if in the absence of any liquid the pressure in the chamber is atmospheric, when the liquid occupies $\frac{1}{2}$ of the volume of the chamber the pressure will increase in the latter to exceed 4 kilograms per square centimetre.

In order that the invention may be more clearly understood, reference will now be made to the

accompanying drawings where various embodiments of the invention are illustrated. In the drawings:—

Fig. 1 shows a plan view, partly in section, of one form of the invention.

Fig. 2 shows an elevation of this arrangement, also partly in section.

Fig. 3 shows a modified construction of the device for opening and closing the inlet and outlet orifices for the liquid.

Fig. 4 shows a plan view, partly in section, of a modified construction employing only a single centrifugal pump.

Referring to Figs. 1 and 2 of the drawings, A and B represent the compressor chambers which are preferably conical in order to force the liquid towards the bottom thereof under the centrifugal action of the eddy currents therein. A cock or plug F permits the emptying of the chamber. This is also facilitated by making the base of the chamber conical as shown. P and P' are two centrifugal pumps serving to pump the liquid from the chambers B to A and A to B respectively, and are driven directly by the motor M through a shaft Z. X is the reservoir in which the compressed air or gas is stored.

The inlet pipes from the pumps P and P' which pass into the chambers are covered by means of valves or caps N, N' respectively, and the suction pipes for each of these pumps are covered by the valves or caps O', O respectively. Each of these valves or caps is provided with apertures T as shown. The valves are connected by pivoted levers E whereby they may be simultaneously opened or closed. R are springs which tend to hold the valves N, N' in the closed position, and their tension may be adjusted from the outside by means of the screws V.

The chambers may be filled with liquid through the filling plug H. S is a spring-pressed suction valve for the air or gas which opens on the slightest reduction of pressure in the chamber A or B. This valve may, alternatively, be controlled by the pressure in the injecting pumps, and in this case the valve is closed as soon as there is pressure in the pump; if there is no pressure the valve opens. With this construction, of course, the spring is reversed.

The air compressed in the chambers passes out through the check valve U, through a pipe line u and through a further check valve U into the reservoir X. In order to prevent any liquid from also passing through pipe u, baffles Y may be provided. Alternatively, a partition may be provided or, preferably, the air and the compressing

liquid never come into contact. This may be effected by providing a container I of rubber or rubberized cloth as shown. This material being located between two equal pressures, it will not 5 be strained any more than the ordinary inner tube of a pneumatic tyre.

The method of operation of the apparatus is as follows. If the different members are in the 10 positions indicated in Fig. 1 the pump forces the liquid from the chamber B to the chamber A. Due to the increase of pressure which is caused by this liquid displacement the valve N is lifted and its apertures T uncovered, whereby the liquid may be forced into the chamber A. Due to the 15 coupling of the valve N with the valve O through the lever E the valve O closes the return orifice of the pump P' and closes it more, the more the pressure rises in A.

When the chamber A is full of liquid the valve 20 N is no longer under pressure and due to the action of the spring R this valve is closed and at the same time the valve O is opened. Due to this action the pump P' is put into operation and repumps the liquid from the chamber A to the 25 chamber B. During this operation the valve N' is opened and the valve O' closed. When the chamber B is full the valve N' closes and the pump P comes into operation again. These operations continue in sequence.

30 Due to the pumping of the liquid into either the chamber A or B, air or other gas therein or in the container I is expelled under pressure and is stored in the reservoir X as will be readily understood without further explanation.

35 The liquid employed may be water which may if desired be mixed with glycerine or another product reducing its evaporation, ethylene glycol, or any other suitable liquid.

Fig. 3 shows a modified construction for the 40 inlet and outlet orifices of the pumps, in which the cap valves N and O are replaced by a system of piston valves.

In the device shown in Fig. 3, the lever E is omitted and the valves N and O of Figs. 1 and 2 45 are replaced by two small integral piston valves N and O. When the piston valve N is moved under the action of the injecting pump, it uncovers its apertures T; at the same time, the piston valve O is moved and covers its apertures. The piston valve O has a larger diameter than 50 that of N in order that the pressure increasing in A may maintain it until the action of the spring R preponderates. In the figure, T' denotes apertures which make it possible for the 55 cylindrical part between the piston valves N and O to communicate with the chamber A.

The dotted line indicates the position of the arrangement formed by the piston valves N and O during the extracting of the liquid.

60 Fig. 4 shows an alternative arrangement of the apparatus in which only a single pump is employed. In this case the pump must be connected to each chamber by a suction pipe and by a pressure pipe. The operation of the apparatus is then the same as in the case of two coupled pumps.

The compressor constituting the subject of the invention offers, amongst other advantages, that of allowing the use of a motor operating at a 70 speed of 3,000 revolutions per minute and of reducing the pulsations of the valves to a fiftieth of what they would be in ordinary compressors. The chambers employed may be light and not very cumbersome, and the pressures being limited, the heating is very low; moreover, the

chambers may offer a large radiation surface. The apparatus does not require any lubrication and does not cause any movement of oil; the compression obtained can be regulated at will and it is not possible to exceed that compression which has been predetermined. 5

I claim:—

1. An hydraulic gas compressor comprising two compression chambers, liquid inlet and outlet means to each of said chambers, liquid conduits 10 connecting the inlet of each chamber with the outlet of the other, pumping means in said liquid conduits, operating to convey liquid through said conduits back and forth between said chambers and means controlling said liquid inlet and 15 outlet means, to reverse the direction of flow of liquid between the chambers when the pressure in the chamber undergoing compression reaches a predetermined value.

2. An hydraulic gas compressor comprising two 20 compression chambers each divided by a deformable membrane into a gas compression space and a liquid container, liquid inlet and outlet means to each of said liquid containers, liquid conduits connecting the inlet of each liquid container with 25 the outlet of the other, pumping means in said liquid conduits, and valve means in said liquid containers controlled by the pressures therein to reverse the direction of flow of liquid therebetween whereby the gas is compressed alternately in said 30 gas compression spaces.

3. An hydraulic gas compressor comprising two compression chambers each divided by a deformable membrane into a gas compression space and a liquid container, liquid inlet and outlet means 35 to said liquid containers, liquid conduits affording two-way communication between said inlet and outlet means, pumping means in said liquid conduits, a quantity of liquid movable by said pumping means back and forth between said liquid 40 containers, and valve means in said liquid containers operating to reverse the direction of flow of liquid between said containers, when the pressure in the container undergoing compression reaches a value approximating to that exerted 45 by said pumping means.

4. An hydraulic gas compressor comprising two compressor chambers each divided by a deformable membrane into a gas compression space and a liquid container, liquid inlet and outlet means 50 to each of said liquid containers, liquid conduits affording two-way communication between said inlet and outlet means, pumping means in said liquid conduits, and valve means in said liquid containers interconnected to close said inlet on opening of said outlet and to open said inlet on closing of said outlet.

5. An hydraulic gas compressor comprising two 60 gas compression chambers each divided by a deformable membrane into a gas compression space and a liquid container, liquid inlet and outlet means to each of said liquid containers, liquid conduits affording two-way communication between said inlet and outlet means, pumping means in said liquid conduits, a rocking lever pivoted in each of said liquid containers carrying at its ends valve means to control said inlet and outlet means and spring loads to normally maintain said inlets closed.

6. An hydraulic gas compressor comprising two 70 gas compression chambers each divided by a deformable membrane into a gas compression space and a liquid container, liquid inlet and outlet means to each of said liquid containers, a centrifugal pump, connections between both the com- 75

pression and suction sides of said centrifugal pump and each of said liquid containers and valve means in said liquid containers to control said connections, operating to reverse the direction of flow of liquid, on the pressure in the liquid container reaching a predetermined value.

7. An hydraulic gas compressor comprising two gas compression chambers each divided by a deformable membrane into a gas compression space and a liquid container, liquid inlet and outlet means to each of said liquid containers, liquid conduits affording two-way communication between said inlet and outlet means, a pump in each of said liquid conduits, a rocking lever pivoted in each of said liquid containers carrying at its ends valve means to control said inlet and outlet means individual to each of said liquid conduits and spring loads to normally maintain each of said inlets closed.
- 10 8. An hydraulic gas compressor comprising two gas compression chambers each divided by a deformable membrane into a gas compression space and a liquid container, each of said compression chambers being provided with baffles to prevent

the gas to be compressed from contacting with the compressing liquid, liquid inlet and outlet means to each of said liquid containers, liquid conduits affording two-way communication between said inlet and outlet means, pumping means in said liquid conduits, a rocking lever pivoted in each of said liquid containers carrying at its ends valve means to control said inlet and outlet means and spring loads to normally maintain said inlets closed.

9. An hydraulic gas compressor comprising two gas compression chambers each divided by a deformable membrane into a gas compression space and a liquid container, liquid inlet and outlet means to each of said liquid containers, liquid conduits affording two-way communication between said inlet and outlet means, pumping means in said liquid conduits, a rocking lever pivoted in each of said liquid containers carrying at its ends valve means to control said inlet and outlet means and spring loads serving as biases connected to said rocking levers at points adjacent to the inlet valves to normally maintain said inlets closed.
